UNITED STATES PATENT OFFICE.

LADISLAS LAKATOS, OF NEW YORK, N. Y.

TYPESETTER'S SCALE.

Application filed March 27, 1922. Serial No. 547,024.

To all whom it may concern:

Be it known that I, LADISLAS LAKATOS, a citizen of the United States, and resident of New York, in the county of Bronx and State 5 of New York, have invented certain new and useful Improvements in Typesetters' Scales, of which the following is a specification.

This invention relates to certain new and 10 useful improvements in rules, more especially in folding rules and has for its main object to provide a rule of the mentioned character which could be effectively and conveniently used by printers for measuring 15 type after being set up.

Another object of the invention is to provide a rule of the mentioned character which is simple and practical in its construction, which has improved means to hold it in 20 its open or closed position, respectively, which can be carried around by the workman very conveniently and which will be easy and cheap to manufacture, durable in use and exact in its measurements.

To obtain the mentioned objects, I provide a rule which may be constructed of two or four equal sections held together by joints suitable to be kept in open or in a short closed form, having means to 25 keep its edges intact and perfect, having end projections to make adaptable to measuring set up type and finally having four different scales alongside of its four edges and thereby representing any four main 30 type measurements used in a printer's shop.

For a full description of the invention and the merits thereof and also to acquire a knowledge of details of construction of the same for effecting the various results 35 mentioned hereinbefore, reference is to be had to the following description and accompanying drawings, forming part of this specification.

While the essential and characteristic features of the invention are susceptible of modification, still the preferred embodiment of my invention is illustrated in the accompanying drawings, in which:—

Fig. 1 is a plan view of my printer's rule in full length open and shown as made of 40 four sections,

Fig. 2 is a plan view of the same in a closed position,

Fig. 3 is a similar view taken from the 45 side,

Fig. 4 is a sectional view of a portion of

my device in a somewhat enlarged scale and the section being taken on the line 4—4 of Fig. 5, and

Fig. 5 is a plan view of the same portion 60 of my device as that shown on Fig. 4.

Fig. 6 is a cross sectional view taken on the line A—A of Fig. 1.

Referring more closely to the drawings, 65 6 indicates the main body of the sections of the rule, being preferably made of wooden strips. Both edges of each strip are covered with a thin metal protection 7 made of sheet metal and being bent over the two surfaces of the strip for a short distance. Said protection is continued at and around 70 the ends of each strip fully covering the ends of the sections as at 8 and forming a pocket into which the wooden strip is pressed and kept in position by being enclosed in the integral sheet metal protection 7 and 8 and having a tight fit therein. The two ends of each adjoining sections are overlapping and a pin 9 is connecting them 75 rotatably and secured to them by any suitable means. Two cooperating impressions 10, 10 Fig. 5 are pressed into the metal covering at the ends of each section, one being inwardly into the material of the section, the other cooperating one in the other section being outwardly and the two fitting 80 into each other Fig. 4. When the rule is opened, or closed fully, said two pairs of cooperating impressions and raised portions at the ends of the sections snap into a 85 fixed position and keep the rule closed or opened as the case may be. If it is desired to open the folder rule or to fold the open one, the cooperating impressions can be 90 forced out of their locked position with a slight pressure sideways on the rule sections and snapped into the desired new position. The metallic covering will keep the rule 95 steadily in an exact and perfect shape and the construction of its joints will make it 100 easy and cheap to manufacture and provide an easily operated and still reliable means for securing the same in the position desired.

The rule may have a scale alongside each 105 of its four edges and thereby facilitate for the printer to make all kinds of measurements with the same rule as against the several rules used at present in printers' 110 shops. For instance, one side of the rule may have scales for measuring agate and 8 point types, the other side may have the

scales for the 6 and 12 point types. At the same time the rule being adapted to be folded, can be carried around conveniently in any pocket of the workman using the same.

5 At one end of my rule I arrange a double projection 11 which can be used to be placed against the types set and the scale put into the right position to read the measurement of the types set. The inside edges of this 10 projection may also be covered with the metallic protection of the last section of the rule as at 12 and insure an exact measurement all the time and a long life to the instrument.

15 Having thus described my invention, what I claim as new and want to protect by Letters Patent, is:—

20 1. In a printer's rule, in combination, two or more longitudinal sections of equal lengths arranged with adjacent ends overlapped, pivots connecting said overlapped ends and lying flush with the outer faces thereof whereby the sections may be folded flat one upon the other, means in connection 25 with said sections for automatically locking them either in extended position or in folded position, each one of the sections alongside each of its longitudinal edges being provided with a different printer's scale 30 adapted to measure a different size of printing type.

25 2. In a printer's rule, in combination, two or more longitudinal sections of equal lengths arranged with adjacent ends overlapped, pivots connecting said overlapped ends and lying flush with the outer faces thereof whereby the sections may be folded 35

flat one upon the other, each one of the sections alongside each of its four longitudinal edges being provided with a different 40 printer's scale adapted to measure a different size of printing type, and a head extended laterally from each side edge of one of the sections and at right-angles thereto, to engage over the types to be measured.

45 3. In a printer's rule, in combination, two or more longitudinal sections of equal lengths arranged with adjacent ends overlapped, metallic strips extending along the side edges of said sections and bent over 50 upon the top and bottom sides thereof, said strips at the ends of the sections extending entirely across the top and bottom sides thereof forming pockets into which the sections are pressed, pivots connecting said 55 overlapping ends and lying flush with the top and bottom sides thereof whereby the sections may be folded flat one upon the other, means in connection with the pocket extensions of said metallic strips for automatically locking the sections either in extended position or in folded position, each 60 one of the sections alongside each of its four longitudinal edges being provided with a different printer's scale adapted to measure 65 a different size of printing type, and a head extended laterally from each side edge of one of the sections and at right-angles thereto, to engage over the types to be measured.

65 Signed at New York in the county of Bronx and State of New York this 13th day of March, A. D. 1922.

70 LADISLAS LAKATOS.
